UNITED STATES PATENT OFFICE.

HARRY B. WIHEBRINK, OF ANDERSON, INDIANA.

COMBINED CRIB AND SWING.

Application filed May 15, 1928. Serial No. 277,958.

This invention relates to a combined crib and swing for children.

An important object of the invention is to provide a device of this character which is capable of general use and which may be readily converted from one to the other of its uses.

A further object of the invention is to provide a device of this character which 10 may be folded into a small compass when not in use so that it may be conveniently stored.

These and other objects I attain by the construction shown in the accompanying drawings, wherein for the purpose of illustration is shown a preferred embodiment of my invention and wherein:—

Figure 1 is a side elevation of a combined crib and swing constructed in accordance with my invention showing the parts in the position which they occupy when the device is used as a crib;

Figure 2 is a plan view thereof;

Figure 3 is a side elevation showing the 25 device folded;

Figure 4 is a side elevation partially in section showing the device in use as a swing;

Figure 5 is an enlarged vertical sectional view therethrough;

30 Figure 6 is a fragmentary side elevation illustrating the manner of connecting the section of the upper frame;

Figure 7 is a detail view showing the manner of connecting the upper ends of the crib straps.

Referring now more particularly to the drawings, the device comprises upper and lower frames, generally designated at 10 and 11. Each of these frames comprises a pair of U-shaped elements, the ends of the arms 40 of which are pivotally connected to one another, as at 13, so as to provide an open rectangular frame, the ends of which may be angularly disposed with relation to one another for a purpose presently to appear.

The upper frame member is provided at its corners with rings 14 adapted to detachably receive snaps of straps 15, by means of which this frame may be suspended. A canvas bag 16 of the proper depth is hemmed, as at 17, at its upper edge about the upper frame member and may have in its bottom a mattress 18 of any suitable character. This mattress should be jointed at its center in alignment with the joints of the

frame members for a purpose presently to appear.

The upper and lower frame members are connected by links 19 and 20, of which the links 19 are pivoted to the lower frame member and the links 20 to the upper frame member. Adjacent ends of the links are pivoted to one another, as at 21, the pivot being spaced from the ends of the links 20 which, at their ends, are provided with notches 22 receiving headed pins 23 carried by the links 19 when the links are in alignment. The sides of the bottom frame are preferably connected by a transverse brace, designated at 24. 70

Secured to the upper frame member at the center thereof and at each side is a plate 25. This plate has at its lower end a cove 26 receiving a headed element 27 carried by the associated link 20 when this link is perpendicularly related to the sides of the frame. At one side of the pivotal connection 13, this plate has an arcuate slot 28 through which extends a bolt 29 carried by the adjacent arm of the U-shaped member at 80 the corresponding end of the frame. 75

Upon this bolt is mounted a thumb nut 30 or similar clamping device for holding the U-frame in adjusted positions with relation to the plate. When the arms of the U-frames of the upper frame member are in alignment with one another, this bolt is disposed at the upper end of the slot.

It will be obvious that when these bolts are in this position and the device is supported by straps engaged with the rings at opposite ends of the upper frame, the upper frame member will provide a very rigid structure. With the parts in this position, a bed is formed. When it is desired to convert the device for use as a swing, the straps are disengaged from the rings 14 of the U-shaped member having the bolts 29 and these bolts are loosened, permitting this U-frame to assume an angle to the other of the frames. Since the corresponding frame member of the bottom frame is supported therefrom, this member will assume a similar angle. Movement of the bolts to the lower ends of the slots terminates the movement of these frame members and leaves the upper ends of the slots free to receive the snaps 31 of the straps 15. With the parts in this position, which is illustrated in Figure 3, one end of the mattress provides a 110

seat while the opposite end thereof forms a leg rest.

Since the construction hereinbefore set forth is capable of a certain range of change and modification without materially departing from the spirit of the invention, I do not limit myself to such specific structure except as hereinafter claimed.

I claim:

1. In a combined crib and swing, upper and lower rectangular frames each comprising a pair of U-shaped sections the ends of the arms of which are pivotally connected to one another, link connections between said frames at the ends and center of the sides thereof, a flexible bag supported from the upper frame, a connection between the sides of the lower frame extending beneath the bag to support the same, and means connecting the sections of the upper frame for maintaining the sections of said upper frame in adjusted positions with relation to one another.

2. In a combined crib and swing, upper and lower rectangular frames each comprising a pair of U-shaped sections the ends of the arms of which are pivotally connected to one another, link connections between said frames at the ends and center of the sides thereof, a flexible bag supported from the upper frame, a connection between the sides of the lower frame extending beneath the bag to support the same, and means connecting the sections of the upper frame for maintaining the sections of said upper frame in adjusted positions with relation to one another, the link connections between said frames being collapsible to permit movement of the frames into superimposed relation.

3. In a combined crib and swing, upper and lower rectangular frames each comprising a pair of U-shaped sections the ends of the arms of which are pivotally connected to one another, link connections between said frames at the ends and center of the sides thereof, a flexible bag supported from the upper frame, a connection between the sides of the lower frame extending beneath the bag to support the same, means connecting the sections of the upper frame for maintaining the sections of said upper frame in adjusted positions with relation to one another, the end corners of the upper frame having means for detachably connecting straps thereto, and means disposed at the

center of the upper frame for connecting the straps of one end of the frame to the frame at the center thereof.

4. In a combined crib and swing, upper and lower rectangular frames each comprising a pair of U-shaped sections the ends of the arms of which are pivotally connected to one another, link connections between said frames at the ends and center of the sides thereof, a flexible bag supported from the upper frame, a connection between the sides of the lower frame extending beneath the bag to support the same, means connecting the sections of the upper frame for maintaining the sections of said upper frame in adjusted positions with relation to one another, comprising plates rigidly secured to one of said sections and having arcuate slots for the passage of bolts carried by the other of said sections, and clamping elements associated with said bolts for maintaining the sections of the upper frame in alignment with one another or in a predetermined angular relation.

5. In a combined crib and swing, upper and lower rectangular frames each comprising a pair of U-shaped sections the ends of the arms of which are pivotally connected to one another, link connections between said frames at the ends and center of the sides thereof, a flexible bag supported from the upper frame, a connection between the sides of the lower frame extending beneath the bag to support the same, means connecting the sections of the upper frame for maintaining the sections of said upper frame in adjusted positions with relation to one another comprising plates rigidly secured to one of said sections and having arcuate slots for the passage of bolts carried by the other of said sections and clamping elements associated with said bolts for maintaining the sections of the upper frame in alignment with one another or in a predetermined angular relation, the end corners of the upper frame having rings, supporting straps having snap hooks to engage said rings, the snap hook of the last named section of the upper frame being engageable in the upper ends of the slots of said plates when the frame is in the last named position.

In testimony whereof I hereunto affix my signature.

HARRY B. WIHEBRINK.
